(57) **CLAIM**

The ornamental design for a front bumper, as shown and described.

DESCRIPTION

FIG. 1 is a front and left-side perspective view of the front bumper of the present invention showing my new design;

FIG. 2 is a front perspective view thereof;

FIG. 3 is a top plan view thereof;

FIG. 4 is a front elevation view thereof;

FIG. 5 is a right side elevation view thereof; and,

FIG. 6 is a bottom plan view thereof.

The broken lines shown in the drawings illustrate environmental structure for the front bumper that forms no part of the claimed design.
